UNITED STATES PATENT OFFICE.

WALTER S. LANG, OF PITTSBURG, PENNSYLVANIA.

APPARATUS FOR SEPARATING BROOM-SPLINTS.

No. 912,692.

Specification of Letters Patent.

Patented Feb. 16, 1909.

Application filed May 21, 1908. Serial No. 434,101.

To all whom it may concern:

Be it known that I, WALTER S. LANG, of Pittsburgh, Allegheny county, Pennsylvania, have invented a new and useful Apparatus for Separating Broom-Splints, of which the following is a full, clear, and exact description, reference being had to the accompanying drawings, forming part of this specification, in which—

10 Figure 1 is a side elevation of one form of machine embodying my invention; Fig. 2 is an end view of the same; Figs. 3, 4 and 5 are detail views of portions of different forms of screens which may be employed.

15 My invention has relation to apparatus for separating broom splints.

Broom splints as they come to the manufacturer are of various sizes and contain many imperfect splints or "flats". For 20 many kinds of brooms it is necessary to more or less closely assort the splints as to size and to also separate therefrom imperfect splints and coarser stems or stalks, which are unfit for use. My invention is designed 25 to provide simple and convenient mechanical means by which this separation can be readily and quickly effected.

The precise nature of my invention will be best understood by reference to the accompanying drawings, in which I have shown one form of machine embodying my invention, and which will now be described, it being premised, however, that the broad 30 features of my invention are susceptible of other embodiments, as will be readily apparent to those skilled in the art.

Referring to Figs. 1 and 2, the numeral 2 designates the frame of the machine, at the upper portion of which are supported 40 a plurality of splint holders or receptacles 3. These receptacles are open at the top and bottom, and may be of any convenient size or shape. A short distance below the lower ends of these receptacles, is a frame 4, 45 which supports a perforated separating screen 5. The frame 4 is supported at one end upon the cam surfaces 6, and at the opposite end or edge is provided with straps 7, which are engaged by eccentrics 8 on a 50 shaft 9 driven by pulleys 10, or other suitable means. As the shaft 9 is revolved, the eccentrics impart a combined endwise and vertical movement to the frame 4 and screen 5, which movement is assisted by the cam surfaces 6 upon which the opposite edge of

the frame 4 is supported. Below the frame 4 is a second frame 11, which carries a table 11^a. This frame 11 and table 11^a may be fixed, but I prefer to suspend them by means of the flexible cords 12 passing over the 60 guide pulleys 13 and connected to a lever 14. This lever is adapted to be engaged with a rack bar 15 secured to one of the legs of the frame 2. When the lever is in the position shown in Fig. 2, the frame 11 and table 11^a 65 will be supported in horizontal position; but by disengaging the lever 14 from the lower notch of the rack bar 15 and moving said lever upwardly the table may be lowered to facilitate the removal of chaff and other 70 dirt which collects thereon, and also to provide more space for pulling the broom splints through the screen.

In operation the broom corn splints to be separated are placed in bunches in the holders 75 or receptacles 3 with their lower ends resting on the upper surface of the screen 5. The agitation of the said screen will cause those splints which are of less diameter than the perforations of the screen to pass through 80 said screen until their butt ends rest upon the table 11^a. Splints of larger diameters, together with coarse stalks or stems, and imperfect splints or flats, will not be able to pass through the screen, but will be retained 85 against its upper surface. After separation has in this manner been effected, the operator pulls the assorted splints, which have passed through the screen or partly therethrough, off from the table 11^a, and 90 those splints which have not passed through the screen are removed from the boxes or holders 3. These latter can then be placed in another machine having a screen of different mesh, or a screen of different mesh 95 can be placed in the same machine, and a further separation effected, these separating operations being repeated until nothing remains in the boxes or holders but the stalks or stems and imperfect splints.

100 A perforated metal plate 5, such as shown in Fig. 3, may be used for the screen, or it may consist of wire netting 5' of proper mesh, as shown in Fig. 4.

In broom manufacture there accumulates 105 more or less waste material, which consists of good splints, which can be utilized by proper separation. This separation is, however, very difficult to effect by hand, owing to the fact that the splints are more or less 110

tangled and are in all sorts of positions with respect to each other. Waste material of this character can be separated and utilized by a machine such as that described. To accomplish this, the waste material is first taken by the operator and by a proper manipulation thereof is separated in bundles in which the splints lie all in the same direction but some of them with their butt ends 10 in one direction and some with their head ends in the opposite direction. Bundles of this material in this condition are placed in the boxes or holders 3, and a screen such as shown at 5^a in Fig. 5, having a relatively 15 coarse mesh, is placed on the frame 4 and is agitated in the manner described. Those splints which have their butt ends downward will readily pass through the meshes of this screen, while those splints which have 20 their head ends down will catch in the wires of the screen and will be prevented from passing therethrough. In this way the material can be readily separated into bundles, in which the splints all lie in the same direction with their butt ends together. Such 25 bundles may be then separated by the use of screens such as shown in Figs. 3 and 4.

The advantages of my invention will be 30 apparent to those skilled in the art who are familiar with the difficulties which have heretofore been attendant upon the assorting or separation of broom splints, since it provides a simple and convenient means by 35 which the separation or assorting can be readily and efficiently effected.

A further advantage of the invention results from the fact that the frame of the machine is so constructed as to permit free access to the space between the screen 5 and 40 the table 11^a, so that the operator can at all times draw out the splints which are passed through or partially through the screen 5 without stopping the machine. The provision of the vertically movable frame 11 45 and table 11^a also facilitates the removal of the splints and the cleaning of the machine.

It will be obvious that various changes 50 may be made in the invention. Thus, any suitable form of holders may be provided for the splints and the screens may be supported and agitated in any desired manner.

I claim:—

1. In apparatus for assorting broom 55 splints, a separating screen, means for imparting a combined vertical and endwise agitating movement to said screen, means for holding the splints to be separated upon the screen, and a vertically movable table below the screen for catching the splints

which pass therethrough; substantially as 60 described.

2. In apparatus for separating or assorting broom splints, a screen, means for holding the splints to be separated or assorted upon said screen, means for agitating the 65 screen, and a table below said screen and arranged to receive the butt ends of the splints which pass therethrough; together with means whereby said table may be moved towards and away from the screen 70 substantially as described.

3. In apparatus for assorting broom 75 splints, a separating screen, a plurality of open bottom boxes or compartments above said screen for holding the splints to be assor- 80 ted, a table or receiving surface below the screen, and means whereby the table or receiving surface may be moved vertically towards and away from the screen, and means for imparting agitation to the screen; substantially as described.

4. In apparatus for assorting broom 85 splints, a separating screen, means for imparting combined vertical and endwise agitating movement to said screen, means for holding the splints to be separated upon the screen, and means underneath the screen for catching the splints which pass therethrough; substantially as described.

5. In a machine for assorting broom 90 splints, a plurality of open bottom holders or receptacles for the splints to be assorted, a perforated screen below the same, means for agitating the screen, and a vertically 95 movable receivable table below the screen together with means for moving said table towards and away from the screen and for holding the same in its different positions; substantially as described.

6. In apparatus for assorting broom 100 splints, a supporting frame a holder or receptacle for the splints to be assorted, a perforated screen below the same, means for imparting a combined vertical and endwise 105 agitating movement to the screen, and a receiving table below the screen, the frame of the machine being open at the sides to permit access to the space between the receiving table and the screen to enable the splints to be removed without stopping the machine; substantially as described.

In testimony whereof, I have hereunto set my hand.

WALTER S. LANG.
